GEORGE M. MARR AND ARTHUR PHELPS MARR, OF NEW YORK, N. Y.

VISIBLE WHISTLE

Application filed May 26, 1930. Serial No. 455,519.

The subject of this invention really has nothing to do with the construction of a whistle, but is an auxiliary to a whistle, the operation of which is by means other than steam.

On Diesel-operated ships, on yachts, and on boats operated by internal combustion motors of any type the whistle, which is so essential, and required by law on all sea-going craft is usually operated either by compressed air, or by electrical means; in other words, the whistles are air whistles or electrical whistles.

In congested traffic, when such a whistle is blown, it is not possible for the navigator of another craft to know from which boat the sound is coming, or what particular whistle has been blown, and as whistles are used for signalling the intentions of the pilot or navigator, it is exceedingly essential that the navigators or pilots or helmsmen of all surrounding boats know when a whistle is blown, and what particular boat intends to accomplish the manœuvre suggested by the whistle signal.

The device, the subject of this invention, then, is an auxiliary adapted to be employed with air or electric whistles, or whistles of any type, or audible signalling means of any type, which do not emit a visual cloud, or energize a visual signal simultaneously with their operation.

We are aware that means have been suggested for making such whistles visible, but we are also aware that the means previously suggested included the use of chemicals, which were objectionable either because of their corrosive action, or because of the deposit left after the operation, or because of the oxidization or plugging which would make the visual device inoperative after a short period of usefulness.

In this present application, we have sought to overcome all of the difficulties that have previously been discovered in such devices, and at the same time, it may produce a simple mechanism and a material to be employed therewith, that would be subject to continuous operation over a long period of time, and that would not clog or stain, or

distribute powder or residue over the boat, or the persons thereon; so, therefore, this present application not only has to do with the mechanism, but has also to do with the material employed.

The following is what we consider the best means of carrying out this invention, and the accompanying drawings should be referred to for a complete understanding of the specification which follows.

In the drawings:

Fig. 1, shows in side elevation, partly in section, one means of carrying out our invention.

Fig. 2, shows a plan view of certain parts of Fig. 1.

Fig. 3, is a similar view showing another means, and

Fig. 4, is a sectional view of a part removed.

Similar reference numerals indicate like parts in all the figures where they appear.

At 1, we show a whistle, which may be of any desired shape or size, and while our device may be operated with an electrically operated whistle, in the drawings we have shown an ordinary air whistle. The air for operating the whistle is received from a source of air supply, through the pipe 2, and a valve 3 allows the air from the pipe 2 to pass onward to the whistle 1.

At 4, we show a T and a short pipe nipple 5 connects this T 4 with a second T 6. It will then be understood that when air is allowed to pass the valve 3, a portion of the air will pass into the whistle, and a portion of the air will pass through the T's 4 and 6.

Connected with the T 6, is a nozzle 7, which is one element of an atomizer. This nozzle 7 is provided with a discharge opening through the restricted portion 8 of the nozzle, and adjacent to this discharge opening is another discharge opening formed in the restricted portion 9 of a short nozzle 10. The short nozzle 10 enters, and is supported in a reservoir 11. Both nozzles may be encased as shown at 12, to prevent mechanical injury, and to prevent the formation of sleet or foreign matter thereon.

In Fig. 2, we show the arrangement of the

nozzles, and in this figure, the slit 13 of the nozzle 10 is shown, and it will be noted that these nozzles are spread outward, and for a purpose that shall appear later.

Connected to the T 6, is a downwardly depending pipe 14, provided with a controlling valve 15. This pipe enters a tank 16, and also entering the tank 16 is a second pipe 17, having a check valve 18 therein.

10 The pipe 17 extending to near the bottom of the tank, extends to near the top of the reservoir 11. The tank 16 is the liquid tank, and in this tank, we place the emulsion which is to be discharged through the atomizer.

15 Air passing through the pipe 14 and controlled by the valve 15, enters the tank 16 at each operation of the whistle, discharging a controlled quantity of liquid from the tank 16 into the reservoir 11.

20 As it is sometimes necessary to arrange the whistle unit high up above the tank 16, the check valve 18 is introduced to assure that the head of liquid in the pipe 17 will not discharge this liquid backward into the tank 16,

25 when the pressure through the pipe 14 is discontinued.

The emulsion which we employ has been carefully selected, not only for its visibility, but also for other desirable qualities. The 30 emulsion consists of a pre-determined quantity of emulsified mineral oil and water, either fresh or salt. The amount of oil employed is such as to make the water practically a non-freeze emulsion.

35 While we have found that a five or ten percent solution of emulsified oil and water operates with entire satisfaction, we do not desire to adhere to just these proportions.

The mixture of the emulsified oil in water 40 results in an emulsion milk-white in appearance, and yet this emulsion does not stain, and because of the content of emulsified oil, the emulsion is less undesirable than clear water.

45 The oil base prevents oxidization of the parts or the formation of ice thereon, and as it serves as a lubricant, there is no fear of corrosion, or of plugging of any of the parts of the device.

50 It will of course be understood that the reservoir 11 is maintained almost full at all times, so that an immediate response is had with every operation of the whistle.

55 For very large boats and for installation with very large whistles, we have found that it is desirable to supply a device that will give forth more than a single fan-shaped spray, such as results from the operation of the mechanism thus far described, and to accomplish this purpose, and to emit a large volume of atomized emulsion, we have constructed the device shown in Figs. 3 and 4.

60 In this exposition, the same type of whistle is shown at 1. The air for operating the whistle is received from an air supply

through the pipe 19, and is controlled by the valve 20. In this construction, the tank 21 is under constant air pressure, the air entering through the pipe 22 and controlled by the valve 23. The emulsion will then pass upward through the pipe 24, its flow being controlled by the valve 25, and liquid will be present under the valve 26.

65 In the operation of this device, both the valves 20 and 26 are simultaneously operated; the one to admit air to the whistle and to the atomizer, and the other to admit liquid to the atomizer reservoir.

70 In the operation of the valve 20, a part of the air will pass upward through the pipe 27, through the nipple 28 in the atomizer, and be spread by hitting the cap or baffle 29. The liquid passing upward through the valve 26 will pass through the nipple 30, into the interior of the reservoir 31. From there, it 75 will pass upward in the space 32, between the inner and outer shells 33 and 34 of the reservoir, to be ejected through the slot 35, which is closely adjacent to the air slot 36.

75 It is not desirable that this device discharge a circular spray, and therefore we provide a filler 37, which may be inserted at any point or on several points in the periphery and the slots 35 and 36 to break up the discharge.

80 At 38, we show a cap over this device, which will serve as does the casing 12, to prevent ice or foreign matter forming or resting on our device. The main supply tank 21 may be provided with a filling nozzle 39, although any other means for filling the tank 85 may be employed, and it may also be provided with a safety valve 40.

85 At 41, we have indicated a smoke stack, and 42 and 43 merely indicate supporting 105 brackets.

90 From the foregoing description, it is believed that the operation of our device will be fully understood; the operation is, however, diametrically opposite to that of the ordinary atomizer, in that it is not our desire to discharge the greatest possible amount of liquid or emulsion.

95 It is our desire to atomize the emulsion to the finest possible degree, and therefore we so proportion our parts that a maximum of air and a minimum of emulsion will be discharged simultaneously, so as to obtain the desired effect, the effect which is that of steam, and from our experience, we have demonstrated that with the use of this particular emulsion, and the structure we have here shown, we do simulate steam, or even improve upon the visibility of steam by the use of an emulsion, which is in itself, milk-white before it is atomized.

100 Of course it will be understood that modifications in all parts may be made within the scope of the appended claims, without de-

parting from the principle or sacrificing the advantages of this invention.

Having carefully and fully described our invention, what we claim and desire to secure by Letters Patent is:—

1. A whistle, and in combination therewith, an atomizing means, a reservoir adjacent thereto, a supply tank, and means for discharging a liquid from said supply tank into said reservoir upon each operation of the whistle.

2. The combination with an air whistle, of a by-pass connected between the whistle valve and the whistle, an atomizer nozzle in said by-pass, a second atomizer nozzle adjacent thereto and across which the air from the first said nozzle is caused to pass, and a fluid reservoir adjacent to said second atomizer nozzle to supply fluid thereto.

3. In a device of the character described, a tank, a pressure supply therefor, a reservoir and means connecting said reservoir with said tank, an atomizing means, one element of which is introduced into said reservoir, and a pressure supply for the other element of said atomizer, and means for controlling the operation of said atomizer, and a whistle operated by said controlling means.

4. In a device of the character described, a whistle, means for supplying a fluid for operating said whistle, and means for controlling said supply, an atomizing means, means for supplying two fluids to said atomizing means and at right angles to each other, one of which shall be under pressure, and means for controlling said pressure supply, and means for periodically admitting said second fluid to said atomizing means.
